Primary Examiner — Michael C Stout

Assistant Examiner — Fitzgerald L Butac

(74) Attorney, Agent, or Firm — Rabin & Berdo, P.C.

(57) **CLAIM**

The ornamental design for a cutting insert for machine tools for metalworking, as shown and described.

DESCRIPTION

1. Cutting insert for machine tools for metalworking

1.1 :Perspective

1.2 : Front

1.3 : Back

1.4 : Top

1.5 : Bottom

1.6 : Left

1.7 : Right

The claimed design has a central hole.

The broken lines show portions of a cutting insert for machine tools for metalworking that form no part of the claimed design.
